The ornamental design for a self-adjusting drawer slide
socket, as shown and described.

(**) Term: **14 Years**

DESCRIPTION

(21) Appl. No.: **29/124,243**

FIG. 1 is a front, top left side perspective view of a
self-adjusting drawer slide socket with the slide in the
left-most position embodying our design;

(22) Filed: **Jun. 5, 2000**

FIG. 2 is a front, top right side perspective view of the
self-adjusting drawer slide socket as seen in FIG. 1 with the
slide in the right-most position;

(51) LOC (7) Cl. **08-05**

FIG. 3 is a top view of the self-adjusting drawer slide socket
as seen in FIG. 2 with the slide in the right-most position;

(52) U.S. Cl. **D8/374**

FIG. 4 is a bottom view of the self-adjusting drawer slide
socket as seen in FIG. 2;

(58) Field of Search D8/374; D6/510;

312/334.1

FIG. 5 is a rear view thereof;

(56) **References Cited**

FIG. 6 is a right side view thereof; and,
